MANIFOLDING DEVICE FOR WRITING MACHINES

Application filed September 23, 1927. Serial No. 221,431.

This invention relates to improvements in manifolding devices and more particularly with reference to some of its specific features, it relates to improvements in a form of transfer or carbon sheet carrier adapted to be combined with a supply pad or tablet for manifolding purposes and having traveler record strips assembled for inscription.

It is a general object of the invention to provide an improved transfer or carbon sheet carrier which is adapted for use in various forms of manifolding writing, and is so constructed that it may be carried by the superposed record strips to support the transfer sheets therebetween in manifolding position, and may be shifted from one manifolding position to another by sliding it longitudinally relatively to the transfer sheets.

A further object of the invention, is to provide an improved carbon or transfer sheet carrier adapted for use in flat or cylindrical platen types of manifolding machines such as typewriters, billing machines, autographic registers, and the like, and which is so constructed and arranged that it, together with the transfer sheet or sheets carried thereby, may be fed forwardly with the record strips past the platen of the manifolding machine so as to release them from frictional restraint whereby the transfer sheets may be adjusted along the record strips from one transfer position to another.

A further object is to provide an improved transfer sheet carrier which is flexible transversely of its length enabling it to conform to a curved path such as the surface of a cylindrical platen, while at the same time providing a satisfactory support for holding one or a plurality of carbon sheets in manifolding relation with reference to the superposed record strips.

Still another object of the invention is to provide an improved form of writing or supply pad for manifold inscription having a plurality of superposed traveler record strips and embodying, in combination, an improved arrangement for supporting one or a plurality of transfer sheets in shiftable manifolding relation with reference to the record strips.

A further object is to provide, in combination with a plurality of superposed traveler record strips, an improved form of carbon block or transfer sheet carrier adapted to support one or more transfer sheets in manifolding relation and having means for shifting the carrier from one manifolding position to another and so mounted with reference to the record strips as to be moved forwardly therewith and thereby.

Other objects will be in part pointed out in connection with the following detailed disclosure of certain illustrative but preferred embodiments of the invention, and will be in part obvious in connection therewith.

The invention accordingly comprises the features of construction, combinations of elements, and arrangement of parts, which will be exemplified in the construction hereinafter set forth and the scope of the application of which will be indicated in the claims.

For a more complete disclosure of the nature, objects and advantages of the invention, reference is had to the accompanying detailed disclosure and to the drawings in which,

Fig. 1 is a plan view of a carbon or transfer sheet carrier constructed in accordance with the invention, and being detached from the record strips with which it is adapted to be assembled for manifolding purposes.

Fig. 2 is a perspective view of the same. Fig. 3 is a fragmentary detailed plan with parts broken away to facilitate disclosure.

Fig. 4 is a perspective diagrammatic view showing the improved manifolding device with the transfer sheet carrier in operative position with reference to the record sheets or strips.

Fig. 5 is a perspective view of a modified form of transfer sheet carrier.

Fig. 6 is a fragmentary plan similar to Fig. 3 but showing a further modified form of the carrier, and,

Fig. 7 is a longitudinal sectional perspective of the form of carrier shown in Fig. 6.

Referring to the drawings for a detailed description of the embodiments of the invention there shown, and first to the embodiment of Figs. 1 to 4 inclusive, one of the improved transfer sheet carriers 10 is shown in

Fig. 4, in combination with a plurality of superposed traveler record strips S folded zigzag into the form of a tablet or supply pack or pad S'. This pad may be utilized as a supply for various types of manifolding machines such as typewriters, billing machines, autographic registers, etc., the free ends of the superposed record strips being led forwardly so as to rest against a writing bed or platen in a manner well known in the art. The carbon or transfer sheets C are interleaved in manifolding relation with the strips S and attached to the carrier 10 which is positioned and arranged to support the transfer sheets in extended position and to move forwardly and backwardly with the record strips as the latter are fed for line spacing in the machine, or for other purposes.

The structural details of the transfer sheet carrier 10 are clearly disclosed in Figs. 1, 2 and 3, said carrier preferably being made of sheet material and being flexible transversely of its length so as to conform to a curved path such as the surface of a cylindrical platen. The carrier 10 may, for example, be made of heavy brown or manila paper so as to be flexible in any direction, but of sufficient weight and strength to function as a support for the relatively lighter and more fragile carbon paper sheets C attached to it, or it may be made of other similar light flexible material such as textile fabric or light fiber board, and it may be and preferably is more flexible transversely of its length than it is longitudinally thereof. The carrier 10, however, will be of sufficient stiffness and strength longitudinally to support the transfer sheets in smooth flat manifolding position between the record strips and also of sufficient strength to enable it to function as a shifter to move the transfer sheets from one manifolding position to another between the record strips.

As shown, the flexible sheet is bent or folded into V-shape, one branch or side 11 being provided with a series of parallel longitudinally extending spaced slits 13 for receiving therethrough the record strips S and providing parallel attaching strips or bars 14 to which the ends of the transfer sheets C are attached as by an adhesive. The attaching ends of the transfer sheets also pass through the slits 13 from the outside of the flap 11 and are attached to the inner surface of the attaching strips 14. The other flap 12 of the V-shaped support overlaps the slits 13 and attached ends of the transfer sheets, thus protecting them from injury and preventing injury thereby of the record strips. In addition to the protection afforded by the flap 12, the attaching ends of the transfer sheets are further protected from injury by extending through the slits 13 and being attached to the inner surface of the flap 11.

One outer transfer sheet may be attached directly to the flap 12 if desired as shown in Fig. 1, and one of the slits 13 may be formed at the apex of the carrier as shown. The protective flap 12 also strengthens and reinforces the carrier. Obviously as many transfer sheets may be attached to the carrier 10 as desired.

The carrier 10 is made of sufficient length so as to project slightly beyond the longitudinal edges of the record strip as shown in Fig. 4, thus forming ears providing lugs or stops 15 lying beyond the edges of the assembled record strips and functioning to shift the transfer sheets from one manifolding position to another along the record strips. The bend or fold of the carrier sheet provides a tubular or angular reenforcement 16 for the lugs 15 as well as for the carrier generally.

When the transfer sheet carrier is assembled with the superposed traveler record strips S as shown in Fig. 4, said strips pass respectively through the slots 13 whereby one of the transfer sheets is interleaved between each two adjacent record strips with its transfer surface positioned against the inscription-receiving area or blank form of the lower strip. Any record or impression then inscribed upon the upper sheet will be transferred to the lower sheet or sheets. Also it will be obvious that the carrier 10 may be entirely supported by the record strips and that the carrier and transfer sheets frictionally engage with the adjacent record strips whereby said carrier and transfer sheets may be carried forwardly and backwardly as the traveler strips are fed in either direction.

In order to illustrate one only of the many manifolding uses to which the supply pad may be put, a cylindrical platen 17 such as used in typewriters and billing machines, etc., is indicated in dot and dash outline in Fig. 4, and a pair of spaced lugs 18 are also similarly shown; both platen and lugs may be mounted on a supporting manifolding machine as desired. The platen 17 provides a support against which the record strips may rest while being written upon and against which the strips may be pressed by means such as provided in various machines of the class mentioned. This pressure imparts a frictional contact between carrier and transfer sheets and the adjacent record strips until the carrier 10 passes entirely beyond the platen when the frictional grip is released whereby the carrier and transfer sheets may then be shifted relatively to the record strips into new transfer position. The lugs or stops 18 may cooperate with the lugs 15 of the carrier 10 so as to check the forward movement of the transfer sheets while the record strips S continue to advance. Inasmuch as the carrier 10 may be adjusted longitudinally of the record strips, and the strips may also be ad-

justed with reference to the carrier, said carrier may be termed a rider.

Thus the transfer sheets and record sheets may be relatively longitudinally shifted to bring fresh sets of recording areas or blank forms on the record strips into record-transferring position. The transfer sheets may, however, be shifted independently of the stops 18 and the combined record strips and transfer sheets may be utilized in connection with other forms of writing support than that furnished by a cylindrical type of platen. Wherever the carrier or transfer sheet positioner 10 may be used, its flexible character permits it to pass with the record strips through curved pathways or over cylindrical surfaces, while the position of the transfer sheets is in no way disturbed. It will be observed that the rearwardly disposed sides or faces of the ends of the carrier 10 are rounded or inclined toward the longitudinal axis of the carrier as indicated at 19 so as to provide clearance surfaces thereby to avoid obstruction with parts of a manifolding machine when the carrier together with the strips are moved rearwardly.

A slightly modified form of the transfer sheet carrier is shown in Fig. 5 being indicated generally at 10a and formed of a single 30 ply of flexible material of a similar nature to that already described in connection with Fig. 1, and also having laterally projecting lugs 15a which are adapted to perform the same function as the lugs 15 above referred to. 35 The carrier 10a may also be formed with rounded or inclined rearward end portions forming clearance surfaces 19a when utilized in a manifolding machine as already referred to. A single carbon or transfer sheet is attached to the carrier 10a as by an adhesive. 40 This form of carrier may be utilized for manifolding where but a single transfer copy is required, or in this form, as well as in the other embodiments of the invention, both 45 sides of the sheet C may be carbonized, enabling two transfer copies to be made by each transfer sheet, one of which will be in reverse. The reverse copy may be made on the back side of a record strip or sheet of 50 parchment or translucent paper in a manner known in the art.

A further modified form of the transfer sheet carrier is shown in Figs. 6 and 7 being indicated generally by reference 10b and being of flexible material similar to that used for the carriers above described. Instead of being formed V-shaped as in Fig. 2, the plies 20 arranged in superposed overlapping parallel relation forming interposed slots or 55 passageways 21 between adjacent plies extending from edge to edge forwardly and rearwardly of the carrier through which the record strips may be threaded in a manner similar to the threading thereof as above described in connection with Fig. 4. These plies 20 are se-

cured together at their ends as by an adhesive as indicated at 22 so as to form a unitary block or support. The ends of the transfer sheets C are attached to the plies 20 within the slots or passageways 20 as indicated at 70 23, these attachments thus being thoroughly protected by the overlying plies.

The plies in this case also preferably are extended at their ends so as to lie beyond the edges of the record strips thus forming lugs 75 15b through which the transfer sheets may be manipulated to shift them from one position to another. Also the ends of the carrier 10b are preferably curved or inclined rearwardly to form clearance surfaces 19b 80 as in the other modifications. This form of carrier 10b is also flexible transversely of its length so as to conform to curved paths as in the forms already described, adapting it for use in various types of manifolding machines. Although the longitudinal axes of the transfer sheet carriers or positioners 10, 10a, 10b may be regarded as extending transversely of the manifolding device or unit 85 since they are shown as being elongated, yet 90 for convenience in description the lengths of these positioners or carriers may be regarded as extending in the same direction as the length of the manifolding device as a whole, including the transfer sheets and the positioner to which they are attached; this applies also to the laterally projecting lugs of the extension 15, 15a, 15b of the different embodiments. Therefore when we say that the 95 positioners and the stop lugs thereof are flexible transversely of their lengths we mean that they may be readily bent or flexed transversely of their longitudinal dimensions so as to assume different positions to conform to an irregular path such for example as the 100 curved path around the well known form of cylindrical platen used in various types of writing machines. It will be noticed that the attachments 22 between the plies 20 are 105 also flexible in nature so as to bend or flex readily transversely of their lengths, that is transversely of the length of the transfer sheet positioner or to carrier 10b. In fact the complete manifolding device or unit comprising the positioner 10b and the carbon 110 sheets C together with the attachments for the latter, is flexible in nature throughout its extent so as to bend or flex transversely of its length, thus readily adapting itself to passage along irregular or curved paths. It 115 will be understood that the disclosure in Figs. 6 and 7, as well as in some of the other views, is partially diagrammatic being exaggerated in thickness or lateral dimension 120 so as to facilitate the disclosure, the complete manifolding device or unit being thin and flexible whereby it may readily pass with the record strips through a shallow or thin passage-way, for example around a cylindrical platen. 125 130

In Figs. 6 and 7, it will be observed that the attachments 22 for attaching the transfer sheets together are positioned transversely of the planes of the transfer sheets C and are spaced apart a distance greater than the width of the active area of each transfer sheet. This arrangement provides a plurality of continuous passage-ways positioned respectively between the adjacent transfer sheets and extending unobstructed through-
10 out the complete length of the transfer unit as clearly shown in Fig. 7. Both the transfer sheets and the plies 20 are entirely free from each other, within the confines of these passage-ways, so as to permit the threading of the record strips S continuously beyond opposite ends of the transfer unit in a manner similar to that disclosed in Fig. 4.

In this embodiment of the invention the plies 20 are preferably relatively superposed with each other and the extensions 15b of these plies in effect form attaching extensions for the respective transfer sheets C positioned beyond the normal active work areas 25 of said transfer sheets at opposite lateral edges of the latter. These attaching extensions are relatively superposed with each other and directly cooperate with the attaching device 22 for maintaining the transfer sheets of the assembly in place. The attachments between these attaching extensions may be of any preferred character, being preferably disposed, as in the case of the adhesive shown, to bind the transfer sheets 30 together in a direction transversely to the plane thereof. These attachments being positioned beyond the lateral edges of the active transfer areas, it will be seen that unobstructed passageways between these transfer areas are provided for the reception of 35 the record strips.

In order to further reinforce the carrier, 10 as disclosed in Figs. 1, 2, 3 and 4, and to hold the protective flap 12 in close cooperative relation with the flap 11, it may in some cases be advantageous to provide means for attaching the protruding ends of the flaps, and such attaching means will preferably be arranged so that the flaps may be secured 45 together after the carrier has been assembled 50 with record strips as shown in Fig. 4. A dry adhesive or gum 15' applied to the inner face of the laterally protruding end portion of one of the flaps 11 or 12 as shown in Figs. 2, 55 3, and 4, may conveniently be used for this purpose, or the adhesive may be applied to both adjacent faces of the end portions of said flaps. When the carrier has been assembled 60 with the record strips S, the attachment may be quickly and easily made by moistening the adhesive and pressing the adjacent faces into adhering contact with each other. This attachment not only assists in 65 holding the protective flap 12 in correct co-

operative position, but it additionally reinforces the carrier and the stop lugs 15.

Since certain changes may be made in the above construction and different embodiments of the invention could be made without departing from the scope thereof, it is intended that all matter contained in the above description or shown in the accompanying drawing shall be interpreted as illustrative and not in a limiting sense. 75

It is also to be understood that the following claims are intended to cover all of the generic and specific features of the invention herein described, and all statements of the scope of the invention which, as a matter of language, might be said to fall therebetween. 80

Having described my invention, what I claim as new and desire to secure by Letters Patent is:

1. A plurality of relatively superposed traveler record strips and a transfer sheet holder engaging and supported by said record strips so as to be movable forwardly and rearwardly thereby and therewith, said holder having checking lugs spaced laterally 90 of the record strips and positioned thereon laterally beyond the record strips when the transfer sheet is supported in manifolding relation with the record strips by said holder. 95

2. A transfer sheet support including a sheet member to which the transfer sheet is attached and having a checking lug with a curved end surface adapted to guide the support past a platen. 100

3. In combination, a transfer sheet support including a sheet member adapted to carry one or more transfer sheets, a transfer sheet attached to said support, a protective overlapping ply, V-connected thereto, and adhesive means for securing the end portions only 105 of the protective ply to the support. 110

4. In combination, a transfer sheet support including a V-shaped sheet member, and at least one transfer sheet having attachment with the said support and extending therefrom at the apex side thereof, and extending beyond the apex. 115

5. A transfer sheet support including a sheet member to which a transfer sheet is attached and having an opening in which one or a plurality of superposed record strips may be received whereby the said support forms a rider movable along said record strips, said support having a protecting ply overlying the transfer sheet attachment. 120

6. A transfer sheet support including a sheet member having openings in which superposed record strips are respectively received, whereby said support forms a rider movable along said record strips and transfer sheets having attachment to said support respectively adjacent said openings, said support having a protecting ply overlying one or more of the transfer sheet attachments. 125

7. A transfer sheet support including a

sheet member having openings in which superposed record strips are respectively received, whereby the said support forms a rider movable along said record strips, and

5 transfer sheet with their ends extending respectively into said openings and having a protecting ply overlapping the attachments of said ends.

8. A transfer sheet having a checking device thereon, said checking device including checking lugs positioned laterally beyond the opposite edges of a record strip when the transfer sheet is arranged in manifolding relation therewith, whereby said lugs may be engaged to shift the transfer sheet relatively to the record strip, said lugs being laterally flexible transversely of their lengths so as to conform to a curved surface or to lie flat.

9. A transfer sheet having an elongated transversely flexible support with its longitudinal axis extending transversely of the transfer sheet, said support having checking lugs positioned at opposite ends thereof and being flexible transversely of their lengths so as to conform to a curved surface or to lie flat, said lugs positioned laterally beyond the opposite edges of a record strip when the transfer sheet is arranged in manifolding relation therewith, whereby said lugs may be engaged to shift the transfer sheet relatively to the record strip.

10. A transfer sheet having attached thereto a laterally extending transversely flexible support, having a laterally flexible checking device for checking the shifting movement of the transfer sheet relatively to a record strip with which it is arranged in manifolding relation, said flexible support having an opening into which the attaching end of the transfer sheet extends.

11. A transfer sheet having a checking device thereon including a flexible support adapted to check the shifting movement of the transfer sheet relatively to a traveler record strip with which it is arranged in manifolding relation, said flexible support having an opening into which the attaching end of the transfer sheet extends and a protective ply for said attaching end carried by said flexible support.

12. A transfer sheet support including a sheet member to which a transfer sheet is attached, said support provided with a protective ply for the transfer sheet attachment, said protective ply extending over the transfer sheet attachment and being free from said attachment so as to permit free passage of record strips between said attachment and said ply and said ply terminating short of the active part of the transfer sheet.

13. A transfer sheet carrier including a plurality of separable superposed plies of sheet material, and being flexible transversely of its length so as to conform to the cylindrical surface of a platen, and transfer sheets

carried by said carrier and having the major portions of their active surfaces exposed in advance of said plies, said carrier having passage-ways through which continuous record strips may extend into manifolding relation with said advance portions of said transfer sheets.

14. A manifolding device including a plurality of superposed transfer sheets having attachments binding said sheets together, said attachments being flexible transversely of the length of the manifolding device so as to conform to a curved path and being positioned transversely of the planes of the transfer sheets and spaced apart laterally of said sheets a distance greater than the width of their working areas, said sheets being free from attachment with each other at all points in longitudinal alignment with said working areas, so as to provide longitudinal passage-ways between the transfer sheets extending continuously from end to end thereof through which continuous record strips may pass.

15. A plurality of relatively superposed traveler record strips and a transfer sheet holder engaging and supported by said record strips so as to be movable forwardly and rearwardly thereby and therewith, said holder being elongated and having its longitudinal axis extending transversely of said record strips and having checking lugs at opposite ends thereof positioned beyond the edges of the record strips when the holder is in operative position, said lugs being flexible transversely of their lengths so as to conform to a curved surface or to lie flat.

16. In combination, a plurality of superposed traveler record strips, a transfer sheet support including a sheet member having openings into which said superposed record strips may be respectively received, whereby the said support forms a rider movable along said record strips, said transfer sheet support being independently supported by the record strips, and transfer sheets having their ends extending respectively into said openings and being attached to said support beyond the mouth of said openings.

17. A manifolding device including a plurality of superposed transfer sheets each having adjacent each lateral edge thereof an attaching extension projecting laterally beyond the normal active work area of the transfer sheet, said respective corresponding attaching extensions being relatively superposed and having attachment with each other at points positioned laterally beyond said normal active work areas, said manifolding device together with said attachment being flexible transversely of their lengths so as to bend back and forth to pass through an irregular path.

18. A manifolding device including a plurality of superposed transfer sheets, each of said sheets having attached at one end there-

- of a flexible sheet supporting member, said supporting members being relatively superposed and extending to points laterally beyond the normal active work areas of the transfer sheets and having attachment with each other at points positioned laterally beyond said work areas, said manifolding device together with said attachment being flexible transversely of their lengths so as to 10 bend back and forth to pass through an irregular path. 75
19. A manifolding device including a plurality of superposed transfer sheets, each of said sheets having attached at one end 15 thereof a flexible sheet supporting member, said supporting members being relatively superposed and extending to points laterally beyond the normal active work areas of the transfer sheets, and having attachment with 20 each other at points positioned laterally beyond said manifolding device and said attachment being thin and flexible transversely of their lengths so as to bend to adapt them to pass over a curved platen, said 25 work areas, said sheet supporting members being free from attachment from each other at points thereof in longitudinal alignment with said normal active work areas so as to provide unobstructed passageways for rec- 30 ord strips between said supporting members. 90
20. A manifolding device including a plurality of relatively superposed flexible transfer sheet supporting members to one of which a transfer sheet is attached, said supporting 35 members extending to points laterally beyond the normal active work area of the transfer sheet and having attachment with each other at points positioned laterally beyond said work area, said manifolding de- 40 vice together with said attachment being flexible transversely of their lengths so as to bend back and forth to pass through an irregular path. 105
21. A device for manifolding inscription 45 and including, in combination, a plurality of relatively superposed, connected plies of thin, flexible, sheet material, at least one of said plies being a transfer ply, said plies having shoulders in superposed relation to each 50 other and positioned laterally beyond the normal work area of said transfer ply. 110
22. A manifolding device including a plurality of relatively superposed plies of flexible sheet material at least one of which is a 55 transfer ply, each of said plies having adjacent each lateral edge thereof an attaching extension projecting laterally beyond the normal work area of said transfer ply, said respective corresponding attaching exten- 60 sions being relatively superposed and having attachment with each other at points positioned laterally beyond said normal work area, said manifolding device and said attachment being flexible so as to bend back 65 and forth to conform to an irregular path, 125
- said attached extensions being formed to provide checking members positioned laterally beyond said normal work area. 70
- In testimony whereof I affix my signature.
